CLAIM

The ornamental design for a cosmetic container, as shown and described herein.

DESCRIPTION

FIG. 1 is a perspective view of a cosmetic container showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken line in FIG. 7 depicts a boundary line, where the area inside of the boundary line does not form any part of the claimed design.

1 Claim, 6 Drawing Sheets(56)
